John P. De Muth, INVENTOR.

BY

Geo. P. Kimmel. ATTORNEY.

UNITED STATES PATENT OFFICE.

JOHN P. DE MUTH, OF BUFFALO CENTER, IOWA.

CIGARETTE-PACKAGE CASE.

Application filed August 10, 1926. Serial No. 123,401.

This invention relates to a cigarette package case, holder, container or envelope hereinafter termed a case, and has for its object to provide, in a manner as hereinafter set forth, a case for receiving and retaining a package of cigarettes until the contents of the package has been entirely removed, and further constructed and arranged to permit of the convenient removal of a cigarette or 10 cigarettes from the package when desired, to prevent the contents of the package from crushing until the last cigarette has been taken out, and to protect the contents of the package from moisture and perspiration.

15 Further objects of the invention are to provide a cigarette package case for the purpose set forth and in a manner as herein-after referred to, which is simple in its construction and arrangement, strong, durable, 20 thoroughly efficient in its use, practical, permitting of the convenient removal of a cigarette from the package of cigarettes, and inexpensive to manufacture.

With the foregoing and other objects in view, the invention consists of the novel construction, combination and arrangement of parts as hereinafter more specifically described, and illustrated in the accompanying drawings, wherein is shown an embodiment 30 of the invention; but it is to be understood that changes, variations and modifications can be resorted to which fall within the scope of the claims hereunto appended.

In the drawings wherein like reference characters denote corresponding parts throughout the several views:

Figure 1 is a side elevation of a case in accordance with this invention, and with a package of cigarettes mounted therein.

40 Figure 2 is a section on line 2—2, Figure 3, with the cigarettes removed.

Figure 3 is a top plan view of the case with a package of cigarettes therein.

Figure 4 is an inverted plan view of the 45 case with the package of cigarettes omitted.

Figure 5 is a side elevation or modified form of case in accordance with this invention.

As is well known a majority of cigarette 50 smokers after purchasing a package of cigarettes removes an end portion of the top of the package to enable them to take out a cigarette when desired. This prevents the cigarettes of the package from becoming dry, which would be the case if the entire top was removed, and further as only a por-

tion of the top is removed, the non-removed portion acts to retain the majority of the cigarettes of the package within the wrapper. With reference to Figure 3, 1 indicates the wrapper of a cigarette package and which has a portion of its top 2 removed to permit of the taking out of a cigarette 3 when desired. When the package of cigarettes is not mounted in a case, container, 60 holder or envelope, the package when carried in the pocket is not protected from moisture and perspiration and the contents of the package are not prevented from crushing or mashing until the last cigarette 70 is removed. To overcome the objections just stated the package of cigarettes is removably mounted in, as well as retained within, a cigarette package case, in accordance with this invention and such case 75 comprises an open bottom body portion referred to generally by the reference character 4 and a closure member 5 for portion of the top of the body portion 4. The body portion 4 is constructed, preferably of leather, possessing a semi-rigid characteristic and the top 5 is formed from a material which insures protection against crushing at the upper portion of the case. The lower end of the body portion 4, that is the open bottom 80 thereof, has its inner face provided with a bead or hem which acts as a means to retain the package of cigarettes therein. The body portion 4 includes a pair of end walls and a pair of side walls, conforms in contour 85 to the shape of the package of cigarettes and the latter snugly engages the inner face of said body portion.

One upper corner of the body portion 4 is cut away, rearwardly at an outward inclination, as at 7, to form a permanently open withdrawal opening to permit of withdrawing the cigarettes 3 from the open top part of the package. The cutting away 90 of one corner of the body portion 4 provides the setting up of one of the end walls of less length than the other and the forming of the side walls with a pair of rearwardly extending edges which merge into the top 100 of the shorter end wall. That corner of 105 the package of cigarettes from which the cigarettes are removed, is torn away so as to conform to the shape of the edge of the cut away portion 7. The cigarettes which are to be removed extend above the edge of 110 the cut away portion 7, see dotted line showing, Figure 2.

As shown in Figures 1, 2, 3 and 4 the body portion is constructed from a length of semi-rigid material, preferably leather, bent upon itself and secured together by suitable cement in a manner whereby the ends will overlap and be secured together, as indicated at 9. The top of the body portion 4 is bent over and secured to the top 5, as indicated at 10. The top 5 is arranged within the upper end of the body portion 4 and one end of the top 5, is beveled and with the bevel forming a continuation of the edge of the opening 7. The bevelled end 11 of the top 5 forms what may be termed one end edge of the opening formed at the upper inner corner of the body portion 4 to permit of the withdrawal of the cigarettes. The bead 6, is provided by overlapping the lower end of the body portion, and securing the overlapped part in position by suitable cement.

In Figure 5 of the drawings the case is shown as having the overlapping ends of the material from which the body portion is constructed secured together by a row of stitching 12, the securing of the overlapping part of the body portion to form the bead by a row of stitching 13, and the securing of the top 5 to the body portion by a row of stitching 14.

With reference to Figure 2, the top of the body portion 4, at the cut away part 7, is inturned, as at 15 and secured in position by suitable cement. In Figure 5 however the inturned parts are secured by the row of stitching 14.

Owing to the providing of the body portion 4, with a cut away part 7 to form an opening to permit extracting a cigarette, one end wall of the body portion 4 is of greater length than the other end wall thereof. That end wall of greater length is indicated at 16 and the end wall of smallest length at 17. The end wall 17 of smallest length is of less length than the length of the package of cigarettes or rather of the cigarettes within the package, so that when the package is mounted in the holder the cigarettes will project above the cut away portion 7, see dotted line showing 8 in Figure 2 and full line showing 18 in Figure 5. This permits of the convenient withdrawal of the cigarette when occasion requires. The length of the top 5 corresponds to the length of that part of the top 2 of the package of cigarettes which is not cut away, severed or removed for the purpose of providing an opening in the top of the package of cigarettes to enable the withdrawal of the cigarettes. As before stated the case corresponds in contour to the shape of the package of cigarettes, and as illustrated is oval in cross section.

The cigarette package case in accordance with this invention permits of the convenient removal of a cigarette from the pack-

age of cigarettes, prevents the contents of the package of cigarettes from crushing until the last cigarette has been taken out, and further protects the contents of the package of cigarettes from moisture and perspiration, then furthermore the case is conveniently handled, and can be conveniently stored within a pocket of a garment, and therefore it is thought that the many advantages of a cigarette package case, in accordance with this invention can be readily understood, and although the preferred embodiment of the invention is as illustrated and described, yet it is to be understood that changes in the details of construction can be had which will fall within the scope of the invention as claimed.

What I claim is:

1. A cigarette package case comprising a receiver for the package of cigarettes and consisting of a flexible body portion open at each end and formed of a pair of side and a pair of end walls, the upper end of one end wall positioned below the upper end of the other end wall, each of said side walls having one upper corner cut away to form a rearwardly extending top edge portion merging at its rear end into the top of said shorter end wall, said rearwardly extending edge portions aligning, a top member positioned within and secured to the upper end of the body portion and extending from the longest end wall to the upper end of said rearwardly extending edge portions and further abutting against said side walls, said top member possessing a characteristic to insure protection against crushing at the upper part of the body portion and forming in connection with said edge portions and the upper end of the shortest end wall a permanently open withdrawal opening for the cigarettes in the package, and said body portion provided therein, above the open lower end thereof with retaining means for the cigarette package.

2. A cigarette package case comprising a receiver for the package of cigarettes and consisting of a flexible body portion open at each end and formed of a pair of side and a pair of end walls, the upper end of one end wall positioned below the upper end of the other end wall, each of said side walls having one upper corner cut away to form a rearwardly extending top edge portion merging at its rear end into the top of said shorter end wall, said rearwardly extending edge portions aligning, a top member positioned within and secured to the upper ends of the body portion and extending from the longest end wall to the upper end of said rearwardly extending edge portions and further abutting against said side walls, said top member possessing a characteristic to insure protection against crushing at the upper part of the body portion and forming

in connection with said edge portion and the upper end of the shortest end wall a permanently open withdrawal opening for the cigarettes in the package, and said body portion provided therein, above the open lower end thereof with retaining means for the cigarette package, said edge portions inclining outwardly from the forward to the rear ends thereof and said top member having a bevelled end registering with the inclination of said edge portions.

3. A cigarette package case comprising a receiver for the package of cigarettes and consisting of a flexible body portion open at each end and formed of a pair of side and a pair of end walls, the upper end of one end wall positioned below the upper end of the other end wall, each of said side walls having one upper corner cut away to form a rearwardly extending top edge portion merging at its rear end into the top of said shorter end wall, said rearwardly extend-

ing edge portions aligning, a top member positioned within and secured to the upper ends of the body portion and extending from the longest end wall to the upper end of said rearwardly extending edge portions and further abutting against said side walls, said top member possessing a characteristic to insure protection against crushing at the upper part of the body portion and forming in connection with said edge portion and the upper end of the shortest end wall a permanently open withdrawal opening for the cigarettes in the package, and said body portion provided therein, above the open lower end thereof with retaining means for the cigarette package, said body portion being continuous and of oval shaped contour.

In testimony whereof, I affix my signature hereto.

JOHN P. DE MUTH.
